UNITED STATES PATENT OFFICE.

DANIEL KOPS, OF NEW YORK, N. Y., ASSIGNOR TO KOPS BROS. INC., OF NEW YORK, N. Y., A CORPORATION OF NEW YORK.

APPAREL GARMENT.

Application filed June 17, 1922. Serial No. 568,936.

To all whom it may concern:

Be it known that I, DANIEL KOPS, a citizen of the United States, residing in the borough of Manhattan, city, county, and State of New York, have invented an Improvement in Apparel Garments, of which the following is a specification.

This invention relates to an apparel garment and more particularly to the form of a corset shown and described in Letters Patent No. 1,432,470 granted to me October 17, 1922. In this style of garment the corset is constructed with a closed back, is provided with elastic inserts extending from the upper to the lower edges of the garment adjacent the front steels, and is fitted with adjusting tension devices by which a pull is effected in both directions from the sides of the garment to adjust the same in position on the body of the wearer. This adjustment causes the garment to properly fit the body and also secures the adjusting devices in the position to cause the same to afford the necessary support to the underlying parts of the body.

The object of my present invention is the provision in a corset garment of this type with insert devices at the back of the garment to cause the same to conform to the hips of the wearer with a yielding effect and to provide a support for the back of the wearer which is yielding in the lower portion and fixed at the upper portion, the construction being also such as to provide for the retaining of the fleshy portion of the body at the back which would otherwise extend over the upper edge of the garment, and the corset made in accordance with this invention will be hereinafter more particularly described.

In the drawing:

Fig. 1 is a perspective view illustrating a corset made in accordance with this invention.

Fig. 2 is a plan view of the corset garment extended.

Fig. 3 is a partial elevation showing the upper portion of the back of the garment, the same being shown on a larger scale than that illustrated in Figs. 1 and 2.

Fig. 4 is a section on line 4—4, Fig. 2.

Fig. 5 is an elevation illustrating the construction of the adjusting straps at the inner sides of the front of the garment, and

Fig. 6 is a partial elevation showing

another form of the construction of the back of the garment.

Referring to the drawing, the corset garment made in accordance with this invention includes the usual front steels 10 and 11 which are fitted, respectively, with stud members 12 and eyes 13 by which the parts of the garment are connected in the usual manner. The front steel section 10 has an extension 14, and the front steel section 11 has a similar extension 15. In the extension 14 there are eyelets 16, and similarly in the extension 15 there are eyelets 17. Below the front steel the front steel section 10 is fitted with a catch 18 adapted to be engaged by a hook 19 similarly placed in the extension 15 below the front steel. A lace 20 may be threaded through the eyelets 16 and 17 to suitably connect these extensions when the garment is in position on the body.

In this form of garment there is an elastic section 23 extending between the front steel section 11 and the side section 22 of the body of the garment. This elastic section may be made of any suitable material, and as in similar forms of this type of garment extends from the upper to the lower edge thereof. In the same manner at the other end of the garment there is an elastic section 21. This extends between the front steel section 10 and the side section 24 of the body of the garment as indicated at 24, and like the elastic section 23 extends from the upper to the lower edge of the garment.

In the left hand side of the garment underlying the elastic section 21 there is an adjusting strap 25. Along one edge this adjusting strap is connected in the garment by the same line of stitching 26 which connects the front steel section to the yielding section. Along the opposite edge of this adjusting strap the same is fitted with a series of eyelets 27. In this form of the garment there is also an anchor strap 28 which is secured in the garment by the same line of stitching 28' which connects the yielding section 21 to the side section 24 of the body of the garment. The forward edge of the anchor strap is provided with a series of eyelets 29, and threaded through these eyelets and the eyelets 27 and 29 is a lace 30 which is also passed through eyelets 31 so as to have the ends of the lace available exteriorly of the garment for effecting the adjustment thereof.

Similarly in the right hand end of the garment there is an adjusting strap 32. Along one edge this is secured in the garment by the same line of stitching 33 which 5 connects the forward edge of the elastic section 23 to the front steel section 11. Along its opposite edge this adjusting strap is provided with a series of eyelets 34. At this 10 end of the garment there is also an anchor strap 35. This is connected in the garment by the same line of stitching 36 which connects the elastic section to the side section 22 of the body of the garment. At its forward edge the anchor strap 35 is fitted with 15 a series of eyelets 37. Through these eyelets 37 and the eyelets 34 a lace 38 is threaded. This lace is also threaded through eyelets 39 so that the extremities of the lace are available exteriorly of the garment for adjusting 20 the same to position.

As hereinbefore stated, the corset to which this invention relates is a closed back garment. The back section is indicated at 40. This back section is fitted with stays 41 and 25 42 running in positions parallel to one another and placed on either side of the central line of the back section. Connected to the back section 40 is an upper section 43 which extends between the back section 40 and the 30 side section 44 of the body of the garment, the latter being connected to the side section 24. The section 43 extends from the upper edge of the garment downwardly a predetermined distance terminating along a line 35 indicated at 45 and in this section 43 there are suitably placed stays 46 preferably in a position which is inclined toward the upper end of the back section 40. Similarly on the other side of the garment there is an upper 40 back section 47. This extends between the back section 40 and the section 48 connected to the side section 22 of the body of the garment. The section 47 like the section 43 extends from the upper edge of the garment a predetermined distance downwardly and terminates along a line 49 which, as will be understood, is the lower edge of this section. In the section 47 there are stays 50 placed in a position oppositely disposed to the stays 46; that is to say so as to be inclined toward the upper edge of the central 55 section 40.

At the back of the garment I employ elastic sections extending from the lower edge 55 of the garment upwardly so as to overlap the lower edges of the upper back sections 43 and 47. One of these elastic sections is indicated at 51 and it is connected to the back section 40 along the line of stitching indicated at 52, the opposite edge of the elastic section 51 being connected to the section 44 along a line of stitching indicated at 53. Similarly the elastic section 54 is connected to the back section 40 along the line of stitching 55 and to the section 48 along the

line of stitching 56. The upper edge of the section 51 is indicated at 57 and the corresponding edge of the section 54 at 58, these edges extending above the lower edges of the corresponding sections 43 and 47 so that 70 the upper portions of the elastic sections 51 and 54 materially overlap the lower portions of the sections 43 and 47. The back central section 40, as will be seen by special reference to Figs. 2 and 3 is provided with extensions 59 and 60, and it is to these extensions 75 59 and 60 rather than to the back section 40 that the adjacent edges of the elastic sections 51 and 54 are connected by the lines of stitching 52 and 55 so that if necessary 80 these lines of stitching may be adjusted by changing the positions of the same without interfering with the construction of the other parts of the back of the garment.

By reference to Fig. 6 it will be seen that the stay members 46 and 50 may be placed in substantially central positions extending from the upper edge of the garment to points below the back elastic inserts 51 and 54 instead of in the diagonally placed or inclined positions as shown in the other figures of the drawing and as hereinbefore described.

It will be understood that with the exception of the parts hereinbefore described as 85 elastic the members of the garment are made of the usual inelastic corset material.

I claim as my invention:

1. In an apparel corset, front steel sections, elastic sections adjacent the front steel 100 sections extending from the upper to the lower edges of the garment and connecting the front steel sections to the body of the garment, devices underlying the said elastic sections for adjusting the garment to position, a central back section, elastic inserts on both sides of the central back section extending from the lower edge of the garment upwardly, inelastic back sections extending on both sides of the central back section 105 from the upper edge of the garment downwardly and underlying the upper edges of the said elastic inserts, and stays placed in the said back inelastic sections for cooperating with the said elastic inserts whereby the 110 elastic inserts maintain the garment in position adjustably from parts below the waistline downwardly and the said stay members through their cooperation with the elastic inserts produce a pocket at the upper edge 115 of the garment for the reception of the flesh of the body of the wearer.

2. In an apparel corset, front steel sections, elastic sections adjacent the front steel 120 sections extending from the upper to the lower edges of the garment and connecting the front steel sections to the body of the garment, devices underlying the said elastic sections for adjusting the garment to position, a central back section, elastic inserts 125

- on both sides of the central back section extending from the lower edge of the garment upwardly, inelastic back sections extending on both sides of the central back section 5 from the upper edge of the garment downwardly and underlying the upper edges of the said elastic inserts, and stay members extending in downwardly diverging positions in the said inelastic back members 10 from the upper edges of the garment to points below the upper edges of the elastic inserts whereby the elastic inserts maintain the garment in position adjustably from parts below the waistline downwardly and 15 the said stay members through their cooperation with the elastic inserts produce a pocket at the upper edge of the garment for the reception of the flesh of the body of the wearer.
- 20 3. In an apparel corset, front steel sections, elastic sections adjacent the front steel sections extending from the upper to the lower edges of the garment and connecting the front steel sections to the body of the 25 garment, devices underlying the said elastic sections for adjusting the garment to posi-
- tion, a central back section, elastic inserts on both sides of the central back section extending from the lower edge of the garment upwardly, inelastic back sections on either side of the central back section extending downwardly a predetermined distance and underlying the upper edges of the said elastic inserts, each inelastic back section having a lateral extension secured to the central back section at one edge and to the other edge of which one edge of an adjacent elastic insert is connected, stay members in the said central back section, and stay members in the said inelastic back sections, the said stay members cooperating with each other and with the said elastic inserts whereby the elastic inserts cause the body of the garment to conform to the body of the wearer from points below the waistline downwardly and create a pocket adjacent the upper edge of the garment for the reception of the flesh of the wearer which would otherwise overlie the upper edge of the garment.

Signed by me this 20 day of May, 1922.
DANIEL KOPS.
